DESIGN FOR A TOASTER

Clarence Karstadt, Glen Ellyn, Ill., assignor to
Noblitt-Sparks Industries, Incorporated, Co-
lumbus, Ind., a corporation of Indiana

Application January 3, 1947, Serial No. 135,926

Term of patent 3½ years

(Cl. D81—10)

To all whom it may concern:

Be it known that I, Clarence Karstadt, a citizen of the United States, residing at Glen Ellyn, DuPage county, Illinois, have invented a new, original, and ornamental Design for a Toaster, of which the following is a specification, reference being had to the accompanying drawing, forming part thereof.

Figs. 1 and 2 are perspective views, taken from opposite corners, of a toaster embodying my new design.

I claim:

The ornamental design for a toaster, as shown.
CLARENCE KARSTADT.
